US00D763251S

(12) **United States Design Patent**
Yamazaki et al.

(10) **Patent No.:** **US D763,251 S**
(45) **Date of Patent:** **** Aug. 9, 2016**

(54) **PORTABLE INFORMATION TERMINAL**

(71) Applicant: **SEMICONDUCTOR ENERGY LABORATORY CO., LTD.**, Atsugi-shi, Kanagawa-ken (JP)

(72) Inventors: **Shunpei Yamazaki**, Tokyo (JP); **Yoshiharu Hirakata**, Kanagawa (JP)

(73) Assignee: **Semiconductor Energy Laboratory Co., Ltd.**, Kanagawa-ken (JP)

(**) Term: **14 Years**

(21) Appl. No.: **29/487,587**

(22) Filed: **Apr. 10, 2014**

(30) **Foreign Application Priority Data**

Oct. 18, 2013 (JP) 2013-024251

CLAIM

We claim, the ornamental design for a portable information terminal, as shown and described.

DESCRIPTION

FIG. 1 is a front view of a portable information terminal showing new design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a top front perspective view thereof; and,

FIG. 8 is a top rear perspective view thereof.

1 Claim, 4 Drawing Sheets
